US0D1063684S

(12) **United States Design Patent** (10) **Patent No.:** **US D1,063,684 S**
(45) **Date of Patent:** **** Feb. 25, 2025**

(54) **RING**

(71) Applicant: **LOUIS VUITTON MALLETIER**,
Paris (FR)

(72) Inventors: **Francesca Amfitheatrof**, Paris (FR);
Paul Harrison, Paris (FR); **Naomi Brown**, Paris (FR)

(73) Assignee: **Louis Vuitton Malletier**, Paris (FR)

(**) Term: **15 Years**

(21) Appl. No.: **29/859,283**

(22) Filed: **Nov. 9, 2022**

(30) **Foreign Application Priority Data**

May 12, 2022 (FR) 20222134
